UNITED STATES PATENT OFFICE.

WESLEY KOUNS, OF SALINA, KANSAS.

STOCK-WATERING TROUGH.

SPECIFICATION forming part of Letters Patent No. 443,446, dated December 23, 1890.

Application filed December 16, 1889. Serial No. 333,978. (No model.)

To all whom it may concern:

Be it known that I, WESLEY KOUNS, a citizen of the United States, residing at Salina, in the county of Saline and State of Kansas, have invented certain new and useful Improvements in Stock-Watering Troughs; and I do hereby declare the following to be a full, clear, and exact description of the invention, such as will enable others skilled in the art to which it appertains to make and use the same.

My invention relates to new and useful improvements in stock-watering troughs; and it consists in the improved construction and arrangement or combination of parts, hereinafter fully disclosed in the description, drawings, and claims.

The objects of my invention are, first, to provide improved means for keeping water in a stock-watering reservoir or trough at a substantially uniform temperature during the different seasons of the year, or cool in warm weather and at about the same temperature, or free from freezing, in cold weather; second, to provide a stock-watering reservoir or trough with outer, intermediate or central, and inner walls or shells for forming two or more air-spaces; third, to provide such a stock-watering trough with a bottom which is raised a considerable distance toward its top, so as to leave a large air chamber or space below said bottom, and, fourth, to provide improved means for connecting and securing the component parts of my stock-watering reservoir or trough. These objects are accomplished by the novel construction and arrangement of the parts illustrated in the accompanying drawings, forming part of this specification, in which the same reference-numerals indicate the same parts, and in which—

Figure 1 represents a vertical section of my improved stock-watering reservoir or trough, showing it in operative position or seated in a cavity in the earth; and Fig. 2, a horizontal transverse section of said trough, the section being taken on a line beneath the water-chamber.

In the drawings, the numeral 1 indicates the entire stock-watering reservoir or trough, which is preferably cylindrical in form, although it may be constructed in any other suitable desired shape. This trough is closed

at its upper end by a top or cover 2, having an annular flange 3 projecting downwardly from its periphery and overlapping the upper end of the outer wall or shell 4 of said trough; 55 also, said top or cover is formed with another inner annular flange 5 on its under side for supporting and spacing or holding apart the intermediate or central wall or shell 6 and the inner wall or shell 7 of said trough, which 60 are respectively placed with their upper ends against the outer and inner sides or faces of said flange 5. The lower ends of these cylindrical walls or shells rest upon blocks 8, formed with curved transverse grooves 9 in their upper faces, within which are fitted the edges of the lower ends of said shells. The reservoir or trough, as thus constructed with three shells, is spaced or formed to contain two air-spaces 10. A suitable number of rods or long 65 bolts 11 are passed through the outer air-space 10 and are formed with screw-threaded upper and lower ends, which extend through the cover 2 of the trough and the blocks 8, and are secured in place by the washers 12 and 70 the nuts 13. These rods or bolts, washers, nuts, grooved blocks, and the flanged top or cover of the trough serve to properly space and rigidly hold the three shells in their proper relative positions when assembled for 75 use, and also to permit of their detachment for cleaning, repair, transportation, and similar purposes.

Interiorly of the inner shell 7 and at or near the mid-length of the trough 1 is suitably secured the bottom 14, which, in connection with the lower portion of said inner shell, forms a large air-space 15 within said trough and beneath the water-chamber 16, this air-space, in connection with the surrounding air-spaces 80 10, practically isolating said water-chamber from the effects of heat and cold. The water-pipe 17, which receives its supply from any suitable source, passes up through this large air-space 15 and enters said water-chamber centrally of its bottom. This pipe along its inner vertical portion is also practically isolated from the effects of heat and cold. Also, said pipe is provided with the inlet-valve 18, secured to the inner end of the lever 19, which 95 is connected to the float 20 by means of the rod 21, these parts operating to regulate the flow

of water into said water-chamber in the same manner as the corresponding devices in the patent granted to me November 2, 1886, No. 351,781.

5 The cover 2 is formed with the openings 22 for receiving and supporting the removable buckets 23, which are formed with small holes in or near their bottoms, which are covered by the flap-valves 24, pivoted to the inner 10 walls of said buckets. These valves admit the inflow of the water while the buckets are in place, but close by the pressure of the water when said buckets are removed for cleaning and the like, and prevent the escape into 15 the water-chamber of any refuse or dirt which may accumulate in said buckets. The cover 2 is preferably made of cast metal and provided on its under side with the re-enforcing rib or strip 25, which may be made of any 20 suitable material for strengthening said cover.

It will be obvious from the foregoing that in the use of my improved stock-watering reservoir or trough it is so placed in a correspondingly-shaped cavity formed in the earth 25 that a sufficient portion of its length will project above the earth's surface to enable stock to easily obtain access thereto; that the water-supply pipe projects downwardly and horizontally, leads to a source of supply for the 30 water, and is embedded in the earth to a sufficient depth to prevent the water passing therethrough from freezing in cold weather and keep the same cool in warm weather, but that this pipe as thus arranged is not always 35 indispensable, as the water may be delivered into the water-chamber in other ways, as through the openings in the cover, and the usefulness of the trough remain the same; that the water-chamber in the form of the in- 40 vention herein disclosed is surrounded by a double air-space and arranged above the large air-space which is formed below its bottom and surrounds the water-supply pipe; that these air-spaces will practically keep the wa- 45 ter in said water-chamber at an even tempera- ture, or prevent the same from freezing in cold weather and keep it cool in warm weather; that the rods or long bolts, the nuts, the top or cover of the trough, and the blocks at the 50 lower end thereof serve to firmly unite or se- cure together the several parts of said trough when operatively assembled; that the use of the last-named devices permit the several parts of the stock-watering trough to be manu- 55 factured, shipped, and sold separately, so as to provide for wear and breakage, to be easily placed together, and also secured in position by an ordinary wrench in the hands of any person of average intellect, and to be easy of 60 removal for cleaning and repairs, and that minor changes in the construction and ar- 65 rangement of the parts can be made without departing from the nature or principle of my invention, such as providing the trough with more than two surrounding air-spaces.

Having thus fully described the construc-

tion and arrangement or combination of the several parts of my improved stock-watering trough, its use, purposes, and advantages, what I claim as new is—

1. In a stock-watering trough, the combination, with a water-chamber, of walls or shells surrounding the same and forming air-spaces, a cover extending over said chamber and closing the upper ends of said shells, and a raised 70 bottom secured to the inner surface of the inner shell and forming an air-space below said bottom, substantially as described.

2. In a stock-watering trough, the combination, with a water-chamber, of walls or shells surrounding the same and forming air-spaces, a cover extending over said chamber and closing the upper ends of said shells, a raised 75 bottom secured to the inner surface of the inner shell and forming an air-space below said bottom, and a water-supply pipe communicating 80 with said chamber, substantially as described.

3. In a stock-watering trough, the combination, with an outer, an inner, and a central wall or shell, of a cover having a peripheral 85 flange overhanging the upper end of the outer shell and an inner flange upon its under side for spacing said inner and central shells, and means for holding said cover in place, sub- 90 stantially as described.

4. In a stock-watering trough, the combination, with an outer, an inner, and a central wall or shell, of a cover having a peripheral 95 flange overhanging the upper end of the outer shell and an inner flange upon its under side 100 for spacing the inner and central shells, a water-chamber having a raised bottom secured to said inner casing, and means for se- 105 curing said shells and cover together, sub- stantially as described.

5. In a stock-watering trough, the combination, with the walls or shells arranged to form air-spaces between them, the cover, the water- 110 chamber having the raised bottom, the sup- porting-blocks, and means for connecting said cover and blocks and holding said shells in place, substantially as described.

6. In a stock-watering trough, the combination, with an outer, an inner, and a central wall or shell and a cover having a peripheral 115 flange overhanging the upper end of said outer shell and an inner flange upon its under side for spacing said inner and central shells, of nutted rods or bolts and supporting-blocks se- 120 cured to the lower ends of said rods or bolts and formed with grooves in their upper sur- faces for supporting and spacing the lower ends of said shells, substantially as described.

7. A stock-watering trough 1, provided with the outer shell 4, the central shell 6, the inner shell 7, the water-chamber 16, having the raised bottom 14, the cover 2, formed with the openings 22 and with the peripheral and inner flanges 3 and 5, the buckets 23, supported in said openings, the supporting-blocks 8, formed with the curved grooves 9 in their upper faces for receiving the lower ends of said 125 130

shells, the rods or bolts 11, formed with screw-threaded upper and lower ends, extended through said cover and blocks and provided with the washers 12 and nuts 13 at their upper and lower ends, and the water-supply pipe 17, entering said water-chamber centrally of its bottom, substantially as described.

In testimony whereof I affix my signature in presence of two witnesses.

WESLEY KOUNS.
